LOOM SHUTTLE CONTROL

Harold C. Robinson, Salem, N. H.

Application August 5, 1933, Serial No. 683,769

7 Claims. (Cl. 139—187)

The present invention relates to shuttle looms and has more particular reference to the shuttle controlling devices thereof.

A principal object of my invention is to provide, in a fly shuttle loom having a shuttle box or shuttle boxes, a novel and improved form of shuttle actuated shuttle checking device which shall also operate as a shuttle release.

A further object of my invention is to provide, in a shifting shuttle box loom having means for positioning the shuttles as they are shifted from active to inactive positions, means for releasing, or at least lessening, the binder pressure on the shuttle being so positioned.

Still further object of the invention is to provide a binder having contained therein a novel and improved shuttle checking and releasing element, which binder shall be equally adaptable for use on single shuttle looms and multiple shuttle shifting-shuttle-box looms.

Further objects of the invention will in part be hereinafter more specifically enumerated or will become obvious as the description proceeds.

For detailed disclosure of the preferred embodiments of my invention, reference may be had to the accompanying drawings, of which:

Fig. 1 is a plan view of the left hand shuttle box and associated parts of a single shuttle loom embodying my invention, the shuttle being absent from the shuttle box;

Fig. 2 is a view similar to Fig. 1 but showing the shuttle in the shuttle box;

Fig. 3 is a horizontal sectional view of the binder of Figs. 1 and 2, detached from the loom;

Fig. 4 is a view in cross section, taken substantially on line 4—4 of Fig. 3;

Fig. 5 is a front elevation of the left hand shuttle boxes of a drop box loom embodying my invention, certain parts being broken away to expose other parts of the mechanism; and

Fig. 6 is a fragmentary plan view of the mechanism shown in Fig. 5.

There is herein disclosed adaptation of my invention, in one of its many forms, to both a single shuttle loom and a multiple shuttle loom. The adaptation to a single shuttle loom is illustrated in Figs. 1-4, inclusive, and this form will be described first.

Such changes as are required to apply the preferred embodiment of my invention to a conventional loom are confined to the shuttle box and accordingly it is unnecessary to show or discuss the component mechanisms of the loom with which my invention is not concerned. I have, Figs. 1 and 2, illustrated the left hand end of a lay

1 which is mounted on lay swords, as 2, for reciprocation toward and from the front of the loom in the usual manner. A shuttle box is carried at each end of the lay, only the left hand shuttle box being illustrated. This shuttle box may be comprised of the usual front box plate 3, back box plate 4 and the metal lay-end 5.

The lay-end 5 is slotted as at 6 to accommodate the usual picker stick 7, which carries a picker 8 for engaging and picking the shuttle 9. A binder 10 is pivoted, as at its outer end, upon a bolt 11 whereby the binder may be swung outwardly by the incoming shuttle to move a finger 12. This finger is a part of the usual protector-rod type of loom protection mechanism which need not be herein disclosed.

The binder 10, which is of my invention, is comprised of an elongated binder body, preferably of wood, having its inner face lined with a suitable friction material 13 such as leather. The shuttle engaging surface at the inner end of the binder is curved as at 14 and projects slightly into the shuttle box when the shuttle is absent therefrom, (see Fig. 1). The incoming shuttle accordingly first engages the curved surface 14 and swings the binder outwardly, i. e. rearwardly to move the finger 12 and thereby prevent operation of the protection mechanism.

The finger 12 yieldingly resists outward movement of the binder from the position shown in Fig. 1 and the protection mechanism may include a stop (not shown) for positively preventing movement of the finger and binder outwardly of the position shown in Fig. 2. The binder accordingly serves to frictionally retard or check the movement of the incoming shuttle. The binder shown departs from usual practice in that instead of forming the binder entirely of one rigid body I have inserted therein an additional shuttle checking element 15.

The binder body is recessed as at 16 to receive the element 15 which is slidably mounted therein for movement longitudinally and laterally of the lay and shuttle. The element 15 may be prevented from dropping out of the recess 16 by any suitable means such as metal plates 17 and 18 secured respectively to the upper and lower surfaces of the binder body as by wood screws 19. The upper plates 17 are bent downwardly, at 20, and the lower plates are bent upwardly at 21, into recesses in the element 15. Flat metal plates 22 and 23 may be secured to the element 15 by screws 24, which plates cooperate with the first mentioned plates to hold the element in the recess 16. A coiled spring 25 may be positioned in a

recess in the binder body to engage a lug 26 on the element 15 and yieldingly urge the latter toward the right hand end of the recess. This spring is intended merely to prevent vibration of 5 the element 15 and may be omitted.

The plates 22 and 23, which are parallel, are inclined at an acute angle to the longitudinal axis of the binder body and constitute cam surfaces. Cooperating cam surfaces, similarly inclined, are 10 formed on the binder body as at 27 and 28.

The incoming shuttle engages the element 15 (or lining thereon) and moves the element bodily longitudinally of the shuttle box. The cam surfaces mentioned serve to also move the element 15 inwardly toward the shuttle to pinch and thereby 15 check the latter. The angle of the cam surfaces may be varied, as may the resistance of finger 12. Depending on these and other factors, the checking action of the element 15 may take place almost entirely after it has been moved to the outer 20 end of the recess 16 or may take place while the element is being so moved. In either event, actuation of the element by the shuttle serves to increase the effective thickness of the binder and, 25 therefore, to increase the effectiveness of the checking action.

It will be apparent that when the shuttle first starts to move out of the shuttle box on the next 30 pick the element 15 will move longitudinally and outwardly, i. e. rearwardly, of the shuttle box and thereby release the binder pressure on the shuttle. Whether this release is only partial or is substantially complete is determined by the length 35 and angle of the cam surfaces and the adjustment of the finger 12, which may be varied as desired.

The foregoing construction serves to very efficiently check the shuttle without unduly wearing the same and, at the same time, imposes much less than the usual resistance to the picking of 40 the shuttle out of the box. As a matter of fact, I have been enabled, by this construction, to accomplish all of the checking action in the shuttle box and thus dispense with the usual check straps or other expensive and troublesome auxiliary 45 checking devices.

The adaptation of my invention to a shifting shuttle box loom, as embodied in the construction shown in Figs. 5 and 6, will now be described.

Such a loom employs alternately active (and alternately inactive) shuttles. The lay 30 carries inner and outer box guides 31 and 32 between which a shuttle box 33 is mounted for vertical reciprocation. The shuttle box is provided with a plurality of shuttle-receiving cells, as 34 and 35, and is shifted up and down by a lifting rod 36, to align one and then the other of the cells with the race plate of the lay. A sliding picker 37, mounted on picker rod 38, is actuated by a connection 39 and picker stick 40. The picker projects into the shuttle box and will engage the point of the shuttle 41 in whichever cell is aligned with the race plate.

The incoming shuttle is received in the shuttle box approximately to the position shown in both 65 Figs. 5 and 6. Thereafter the picker is disengaged from the shuttle in the usual manner and the shuttle box is shifted up or down, as the case may be, before another shuttle is picked. The 70 box guide 32 is provided with a rearwardly projecting portion 42 on which are formed inclined shuttle positioning surfaces 43 and 44. As the shuttle box moves up or down the tip of the shuttle which is being moved from active to inactive 75 position engages one or the other of the surfaces

43, 44 and the shuttle is thereby cammed longitudinally of the shuttle box to a predetermined position wherein the tip of the shuttle can just contact a vertical guide surface 45.

The positioning of the shuttle longitudinally of 5 the shuttle box in the manner indicated is done for several purposes. Among these may be mentioned the necessity of having the shuttle occupy the same position each time for proper cooperation with a feeler (not shown) and the necessity 10 of having the shuttle positioned away from the end of the picker when the shuttle is shifted to or past the picker by the shifting of the shuttle box. Such positioning means, and the other parts of the shuttle box thus far described, are old and 15 well known in the art. The protection mechanism, of which finger 46 is a recognized part, is likewise old and well known.

Each cell of the shuttle box is provided with a binder. The upper binder 47 and the lower binder 20 48 are pivoted at their left hand ends, as at 49, and each binder is provided with a movable shuttle checking and releasing element 50. Outward movement of the binder may be limited by a pin 51.

The binders 47 and 48, including the elements 25 50 are herein shown as being identical with the binder shown in Figs. 1-4 inclusive, except that the binders 47 and 48 are reversed so as to fit in the front of the shuttle box. Consequently, further detailed description of these binders should 30 be unnecessary.

The shuttle checking mechanism of my invention, when applied to a shifting shuttle box loom, is possessed of the same advantages as when applied to a single shuttle loom and is possessed of 35 one further very important advantage over prior art constructions, as follows:

In prior constructions the binder pressure on the shuttle being moved from active to inactive 40 position imposed considerable resistance to the longitudinal positioning of the shuttle by guides 43, 44 or their equivalent and such resistance caused rapid wear or mutilation of the guides and the shuttle tips. My invention, on the other hand, provides means for releasing or lessening, 45 the binder pressure on the shuttle simultaneously with the positioning of the same. There is, therefore, in my construction, much less resistance to longitudinal movement of the shuttle by the positioning means with a resultant substantial lessening 50 of the mutilation of guides and shuttles.

It will be understood that numerous changes may be made in the constructions herein disclosed, the true scope of my invention being defined in the appended claims.

I claim:

1. In a loom, the combination of the shuttle and the lay having a shuttle box at one end thereof, with a binder in said shuttle box, a shuttle checking element supported in said shuttle box for movement longitudinally thereof by the incoming shuttle, and cooperating cam surfaces on said binder and said element active upon longitudinal movement of the latter by the incoming shuttle 65 thereby to pinch and thereby check the shuttle.

2. In a loom, the combination of the shuttle and the lay having a shuttle box at one end thereof, with a binder in said shuttle box, a shuttle checking element slidably supported by said binder in the path of the incoming shuttle, and cooperating cam surfaces on said binder and said element which surfaces are active upon engagement of 70 said element by the incoming shuttle to move the 75

element laterally to pinch and thereby check the shuttle.

3. In a loom, the combination of the shuttle and the lay having a shuttle box at one end thereof, with a binder in said shuttle box, and a shuttle checking and releasing element loosely supported by said binder and movable bodily longitudinally and inwardly of said shuttle box by the incoming shuttle for checking the latter, said element moving longitudinally and outwardly of said shuttle box with the outgoing shuttle for releasing the latter as the shuttle is picked from the shuttle box.

4. A loom binder comprised of an elongated binder body having a recessed shuttle engaging surface and a shuttle actuated checking and releasing element slidably mounted within said recess for movement by the shuttle in a direction at an acute angle to the longitudinal axis of the binder body.

5. A loom binder comprised of an elongated binder body having a recessed shuttle engaging surface and a shuttle actuated checking and releasing element slidably mounted within said recess, said binder body and said element being provided with cooperating cam surfaces defining the path of movement of the said element, said

path being at an acute angle to the longitudinal axis of the binder body.

6. A loom binder comprised of an elongated binder body having a recessed shuttle engaging surface and a shuttle actuated checking and releasing element slidably mounted within said recess, said binder body and said element being provided with cooperating cam surfaces serving to force the said element laterally in a direction to increase the effective thickness of the binder as 10 said element is given its shuttle checking movement.

7. In a loom, the combination of the lay with a shifting shuttle box having a plurality of shuttle receiving cells each of which is provided with a 15 binder, active and inactive shuttles, means for moving an active shuttle lengthwise to a predetermined position in its respective cell as said shuttle is shifted from active to inactive position, each of said binders being provided with a shuttle 20 actuated shuttle checking and releasing slide movable longitudinally and laterally of the shuttle box for checking a shuttle as its enters the respective shuttle box cell and releasing the shuttle as the latter is moved by said first mentioned 25 means.

HAROLD C. ROBINSON.
